UNITED STATES PATENT OFFICE.

ARTHUR J. ZIPP, OF CHARLEVOIX, MICHIGAN.

HOISTING APPARATUS FOR RAISING SUNKEN LOGS AND THE LIKE.

1,406,714.

Specification of Letters Patent. Patented Feb. 14, 1922.

Application filed December 26, 1919. Serial No. 347,497.

To all whom it may concern:

Be it known that I, ARTHUR J. ZIPP, a citizen of the United States, residing at Charlevoix, county of Charlevoix, State of Michigan, have invented certain new and useful Improvements in Hoisting Apparatus for Raising Sunken Logs and the like, of which the following is a specification.

This invention relates to improvements in hoisting apparatus for raising sunken logs and the like.

The main objects of this invention are:

First, to provide an improved apparatus for raising sunken logs and the like which lie upon or are embedded in the bottom of lakes and rivers, there being certain lakes and streams where lumbering operations were formerly conducted which contain a great many such logs.

Second, to provide an improved hoisting apparatus by means of which sunken logs may be quickly and conveniently raised and transported to shallow water from which they may be lightered or otherwise removed to a mill.

Further objects, and objects relating to structural details, will definitely appear from the detailed description to follow.

I accomplish the objects of my invention by the devices and means described in the following specification. The invention is clearly defined and pointed out in the claims.

A structure which is a preferred embodiment of my invention is clearly illustrated in the accompanying drawing forming a part of this specification, in which:

Fig. I is a plan view of a structure embodying the features of my invention, various parts being shown conventionally, certain parts being broken away and other parts omitted for convenience in illustration.

Fig. II is a front view with parts being broken away and other parts omitted and shown conventionally for convenience in illustration.

In the drawing similar reference characters refer to similar parts throughout the several views.

Referring to the drawing, I provide a pair of scows 1-1 rigidly connected in a spaced relation by means of the cross beams 2 and the platform 3 to provide a space 4 between them so that a log or other object may be raised between them and towed or carried along in that position.

I provide paddle wheels 5-5 disposed at

the outer side of each scow. These paddle wheels are protected by the side rails 6, the platform 3 being extended to these rails. The paddle wheels are preferably arranged so that their lower edges do not extend below the bottoms of the scows, the scows thus serving as protecting means therefor. The rails 6 converge toward each end and serve as buffers for the scows. Housings 7 are provided for the paddle wheels.

The engine 8 is shown conventionally as of the internal combustion type. The driving shaft 9 is mounted to extend transversely across the space 4 between the scows, it being made up of sections connected by clutches 10 and 11, the clutches being shown conventionally. These clutches 10 and 11, generally known as marine clutches, also serve as a reversing means. The engine is connected to the intermediate section 12 of the driving shaft between the clutches by means of the chain 13 and suitable sprockets.

The hoisting drum shaft 14 is mounted transversely of the scows to extend across the hoisting space. The winding drum 15 is centrally located above this space. This winding drum shaft has a section 16 connected to the section on which the drum 15 is mounted, by means of the clutch 17 and to the driving shaft by means of the sprocket chain 18 and suitable sprockets. The clutch 17 as illustrated is of the cone friction type. A friction clutch in this relation is of great advantage in handling the log. One of the paddle wheels is connected to the drum shaft by means of the clutch 19 while the other paddle wheel is connected to the driving shaft by means of the sprocket chain and suitable sprockets. The hoisting drum shaft is provided with a ratchet wheel 21 and a coacting dog 22 having a foot piece 23 by means of which the ratchet may be released to allow free running of the drum as in paying out the hoisting cable 24 when the clutch 17 is released.

The parts are shown mainly in conventional form as the structural details may be greatly varied. I preferably use in this connection the logging grapples shown in my application for Letters Patent filed concurrently herewith or that shown in Letters Patent No. 1,266,650, issued to me May 21, 1918. The inner sides of the scows are inwardly inclined at 25 so that in hoisting a log it is not likely to catch on the bottoms of the scows and thereby injure the same.

With my improved hoisting apparatus, logs embedded in rivers and streams may be quickly and economically raised and transported to shallow water from which they 5 may be removed by lighters or drawn upon the land or otherwise as desired. The paddle wheels may be driven independently or simultaneously so that the scows may be manipulated to the best of advantage in raising 10 and also in depositing the logs.

I have illustrated and described my improvements in the form in which I have embodied the same in practice. I have not attempted to illustrate or describe certain 15 adaptations and modifications which I contemplate, as I believe the disclosure made will enable those skilled in the art to which my invention relates to embody or adapt the same as may be desired.

20 Having thus described my invention, what I claim as new and desire to secure by Letters Patent is:

1. In a hoisting apparatus of the class described, the combination of a lighter comprising a pair of scows connected side by side in a spaced relation permitting the hoisting of an object between them, each scow being provided with a propeller wheel disposed centrally relative to its length and 25 at the outer side thereof, a sectional driving shaft disposed transversely of the scows and extending across the space between them and comprising an intermediate section connected to a source of power, and end sections 30 connected to the intermediate section by clutches whereby the end sections may be driven together or independently, driving connections for one of said end sections to the shaft of one propeller wheel, a jack 35 shaft, driving connections for the other end section to said jack shaft, said jack shaft being aligned with the shaft of the other propeller wheel and detachably connected thereto by means of a clutch, a drum shaft 40 disposed across the space between the scows centrally relative to the length thereof and in alignment with said jack shaft, a friction clutch connecting said drum shaft to said jack shaft, and a ratchet means for controlling said drum shaft.

45 2. In a hoisting apparatus of the class described, the combination of a lighter comprising a pair of scows connected side by side in a spaced relation permitting the hoisting of an object between them, each scow being provided with a propeller wheel disposed centrally relative to its length and at the outer side thereof, a sectional driving shaft disposed transversely of the scows 50 and extending across the space between them and comprising an intermediate section connected to a source of power, and end sections connected to the intermediate section by clutches whereby the end sections may be driven together or independently, driving

connections for one of said end sections to the shaft of one propeller wheel, a jack shaft, driving connections for the other end section to said jack shaft, said jack shaft being aligned with the shaft of the other propeller wheel and detachably connected thereto by means of a clutch, a drum shaft disposed across the space between the scows centrally relative to the length thereof and in alignment with said jack shaft, and a clutch connecting said drum shaft to said jack shaft.

3. In a hoisting apparatus of the class described, the combination of a lighter comprising a pair of scows connected side by side in a spaced relation permitting the hoisting of a log between them each scow being provided with a propeller wheel disposed centrally relative to its length and at the outer side thereof, a driving means comprising a sectional driving shaft disposed transversely of the scows and comprising an intermediate section connected to a source of power, and end sections connected to the intermediate section by clutches whereby the end sections may be driven together or independently, driving connections for one of said end sections to one propeller wheel, a jack shaft, driving connections therefor to the other propeller wheel including a clutch, 90 driving connections for the other end section to said jack shaft, a drum shaft disposed across the space between the scows centrally relative to the length thereof, a friction clutch connecting said drum shaft 95 to said jack shaft, and a ratchet means for controlling said drum shaft.

4. In a hoisting apparatus of the class described, the combination of a lighter comprising a pair of scows connected side by side in a spaced relation permitting the hoisting of a log between them each scow being provided with a propeller wheel disposed centrally relative to its length and at the outer side thereof, a driving means comprising a sectional driving shaft disposed transversely of the scows and comprising an intermediate section connected to a source of power, and end sections connected to the intermediate section by clutches whereby the end sections may be driven together or independently, driving connections for one of said end sections to one propeller wheel, a jack shaft driving connections therefor to the other propeller wheel including a clutch, 105 driving connections for the other end section to said jack shaft, and a drum shaft disposed across the space between the scows centrally relative to the length thereof, and a clutch connecting said drum shaft to said 110 jack shaft.

5. In a hoisting apparatus of the class described, the combination of a lighter comprising a pair of scows connected side by side in a spaced relation permitting the 130

- hoisting of an object between them, each scow being provided with a propeller wheel, a sectional driving shaft disposed transversely of the scows and extending across the space between them and comprising an intermediate section connected to a source of power, and end sections connected to the intermediate section by clutches, driving connections for one of said end sections to one propeller wheel, a jack shaft, driving connections for said jack shaft to the other propeller wheel including a clutch, driving connections for the other end section to said jack shaft, a drum shaft disposed across the space between the scows, driving connections for said drum shaft to said jack shaft including a friction clutch, and a ratchet means for controlling said drum shaft.
6. In a hoisting apparatus of the class described, the combination of a lighter comprising a pair of scows connected side by side in a spaced relation permitting the hoisting of an object between them, each scow being provided with a propeller wheel, a sectional driving shaft disposed transversely of the scows and extending across the space between them and comprising an intermediate section connected to a source of power, and end sections connected to the intermediate section by clutches, driving connections for one of said end sections to one propeller wheel, a jack shaft, driving connections for said jack shaft to the other propeller wheel including a clutch, driving connections for the other end section to said jack shaft, a drum shaft disposed across the space between the scows, and driving connections for said drum shaft to said jack shaft.
7. In a hoisting apparatus of the class described, the combination of a lighter comprising a pair of scows connected in a spaced relation so that a log or other object may be raised between them each scow being provided with a propeller, a drum shaft disposed across the space between said scows, a driving means for said drum shaft and propellers comprising a jack shaft, driving connections therefor to said drum shaft including a friction clutch, a sectional driving shaft comprising an intermediate section connected to a source of power, end sections connected to the intermediate section by clutches, one of the end sections having driving connection with said jack shaft and the other with one of the propellers, and driving connections with said jack shaft to the other propeller.
8. In a hoisting apparatus of the class described, the combination of a lighter comprising a pair of scows connected in a spaced relation so that a log or other object may be raised between them each scow being provided with a propeller, a drum shaft dis-
- posed across the space between said scows, a driving means for said drum shaft and propellers comprising a jack shaft, driving connections therefrom to said drum shaft a sectional driving shaft comprising an intermediate section connected to a source of power, end sections connected to the intermediate section by clutches, one of the end sections having driving connection with said jack shaft and the other with one of the propellers, and driving connections for said jack shaft to the other propeller.
9. In a hoisting apparatus of the class described, the combination of a lighter comprising a pair of scows connected in spaced relation so that a log or other object may be hoisted between them, propellers disposed at the outer sides of said scows and centrally relative to their length, a drum shaft disposed centrally and in alignment with the shaft of one of said propellers, a jack shaft disposed in alignment with said drum shaft and the shaft of one of said propellers, a friction clutch connecting said jack shaft to said drum shaft, a clutch connecting said jack shaft to the propeller shaft with which it is aligned, a driving shaft, driving connections therefor to said jack shaft and the other propeller wheel including clutches.
10. In a hoisting apparatus of the class described, the combination of a lighter comprising a pair of scows connected side by side in a spaced relation permitting the hoisting of an object between them each scow being provided with a propeller disposed centrally relative to its length and at the outer side thereof, a drum shaft disposed across the space between the scows centrally relative to the length thereof, driving means for said propellers and driving means for said drum shaft including a friction clutch.
11. In a hoisting apparatus of the class described, the combination of a lighter comprising a pair of scows connected side by side in a spaced relation permitting the hoisting of an object between them, each scow being provided with a propeller disposed centrally relative to its length and at the outer side thereof, a drum shaft disposed across the space between the scows centrally relative to the length thereof, driving means for said propellers and driving means for said drum shaft.
12. In a hoisting apparatus of the class described, the combination of a lighter comprising a pair of scows connected side by side in a spaced relation permitting the hoisting of an object between them, each scow being provided with a propeller disposed centrally relative to its length and at the outer side thereof, a drum shaft disposed across the space between the scows centrally relative to the length thereof, driving means for said propellers whereby they

may be driven together or independently, and driving means for said drum shaft.

13. In a hoisting apparatus of the class described, the combination of a lighter comprising a pair of scows connected side by side in a spaced relation permitting the hoisting of an object between them, each scow being provided with a propeller, a drum shaft disposed across the space between the scows, driving means for said propellers whereby they may be driven together or independently, and driving means for said drum shaft disposed across the space between the scows, driving means for said propellers whereby they may be driven together or independently, and driving means for said drum shaft including a friction clutch, and a ratchet means for controlling said drum shaft.
14. In a hoisting apparatus of the class described, the combination of a lighter com-

prising a pair of scows connected side by side in a spaced relation permitting the hoisting of an object between them, each scow being provided with a propeller, a drum shaft disposed across the space between the scows, driving means for said propellers whereby they may be driven together or independently, and driving means for said drum shaft.

In witness whereof, I have hereunto set my hand and seal in the presence of two witnesses.
